Primary Examiner — Clare E Heflin(74) *Attorney, Agent, or Firm* — Michael Best & Friedrich, LLP(57) **CLAIM**

We claim the ornamental design for an illuminating bollard, as shown and described.

DESCRIPTION

FIG. 1 is an upper perspective view of an illuminating bollard showing the new design.

FIG. 2 is a side elevation view of the illuminating bollard shown in FIG. 1.

FIG. 3 is a plan view of the illuminating bollard shown in FIG. 1; and,

FIG. 4 is a lower perspective view of the illuminating bollard shown in FIG. 1.

The elements shown in broken lines are included for the purpose of illustrating portions of the illuminating bollard that form no part of the claimed design.
